(57) **CLAIM**

The ornamental design for USB charging connector for e-vapor device, as shown and described.

DESCRIPTION

FIG. 1 is a first top perspective view of a USB charging connector for an e-vapor device, showing our new design;

FIG. 2 is a second top perspective view thereof;

FIG. 3 is a third top perspective view thereof;

FIG. 4 is a bottom perspective view thereof;

FIG. 5 is a top view thereof;

FIG. 6 is a bottom view thereof;

FIG. 7 is a back view thereof;

FIG. 8 is a front view thereof;

FIG. 9 is a left side view thereof; and,

FIG. 10 is a right side view thereof.

The portions of the design shown in broken lines form no part of the claimed design.

1 Claim, 7 Drawing Sheets
